UNITED STATES PATENT OFFICE.

WILHELM VOLLMER, OF BROOKLYN, NEW YORK.

MACHINE FOR BENDING ANGLE-IRON.

SPECIFICATION forming part of Letters Patent No. 709,282, dated September 16, 1902.

Application filed May 31, 1902. Serial No. 109,658. (No model.)

To all whom it may concern:

Be it known that I, WILHELM VOLLMER, a citizen of the United States, residing in New York, borough of Brooklyn, in the State of New York, have invented certain new and useful Improvements in Machines for Bending Angle-Iron, of which the following is a specification.

This invention relates to improvements in that type of bending-machine illustrated and described in United States Letters Patent No. 699,858, granted to me May 13, 1902. In further developing this style of machine it was found desirable to provide, especially for bending heavy angle-iron, further means for maintaining the iron in proper position during the bending operation, as the iron has a very strong tendency to buckle out of shape and out of position in the machine, and also to provide means for preventing the stretching of the metal at the bend. For carrying out these objects I change the position of the hinge of the presser-plate or supplemental operating-arm by which the stock is retained, the said hinge being now arranged so that said presser-plate swings uniformly toward both of the working faces of the forming-block instead of swinging toward one face directly and the other laterally, and, secondly, I provide two rests for the metal, one rest upon the bending-lever and the other at the opposite side of the forming-block, so that the stock is retained between said rests and the presser-plate. A gage is also provided at the opposite end of the metal from the rest upon the bending-lever, which latter rest acts as a gage for the forward end of the metal and effectually blocks the same against outward movement, so that by the same I am enabled to forcibly upset the horizontal flange of the iron at the bend and obviate the undue stretching of the vertical flange, which has been a great disadvantage heretofore in the bending of angle-iron.

The invention consists, further, in certain other combinations of parts, which will be fully described hereinafter and finally pointed out in the claims.

In the accompanying drawings, Figure 1 is a side view of my improved machine. Fig. 2 is a top view of the same. Fig. 3 is a horizontal section on line 3-3, Fig. 1. Fig. 4 is

a section through the forming-block, guide-block, and bending-lever, the latter of different form from that in Figs. 2 and 3; and Figs. 5 and 6 are perspective views of an angle-iron before and after bending.

Similar letters of reference indicate corresponding parts.

In the drawings, A indicates the base-plate or bed of the machine, which is supported on suitable feet *a* and provided at one end with a longitudinal groove or guide-slot *a'* and with recessed guideways *a''*, one at each side of the slot at the under side of the base or bed A. Upon the base-plate is mounted, at the upper side of the same, a guide-block B, and upon said block is located a top plate C. Said block and plate are secured to the base A by bolts *n* *n'* or any other suitable means. Between the base A and top plate C is pivoted the bending-lever D by means of trunnions *i* *i'*. When in retracted position, the lever enters a suitable recess in the guide-block.

E indicates the forming-block. The same is mounted at the upper side of the base or bed and is provided with a downwardly-extending shank *e* and a flange *e'*, adapted to slide in the guideways *a''*, whereby the block is guided. For adjusting and retaining the guide-block in position a retaining member in the form of a rod *d* is provided, which is threaded at its outer end and engages a threaded sleeve *d'*, secured to the lower end of the block E below the bed. At its opposite end the rod *d* passes through a bearing *d''* of the base or bed A and is provided at one side of said bearing with a collar *d'''* and at the other side with a hand-wheel *d'''*. For accommodating the metal the upper edges of the working faces *n* *n'* of the forming-block are rounded off, as shown.

F indicates the presser-plate, which, as above referred to, is pivoted so as to swing equally toward both bending-faces of the forming-block, so that when the iron is bent the buckling of the flange is equally resisted at both sides of the bending edge or corner *e''* of the block and the plate cannot tilt upwardly at either side independent of the other during the bending operation. For maintaining the plate in position the same is hinged over its entire width and for the full

width of the bending-faces or working faces n^3 n^5 of the block. The plate is provided with an arm or handle f' , which extends at right angles to the hinge f , so that the line 5 of pressure when the plate is pressed downwardly passes directly through the point of the plate F adjacent the bending-corner e^2 . For retaining the plate in depressed position a screw-eye m is screwed into the top plate 10 and a link m' located in said eye, which link is adapted to be placed over the end of the arm or handle f' , as indicated in Figs. 1 and 2. The link may be provided at its upper end with a suitable handle for conveniently 15 operating the same, if desired. The screw-eye is screwed loosely into the top plate, so that when thicker or thinner iron is to be worked the link may be adjusted in vertical direction by turning the same and the eye 20 so as to bring the presser-plate into position for holding the iron firmly. It is not necessary that the presser-plate bear directly upon the entire upper face of the metal. For upsetting the metal at the bend and for stopping the presser-plate at the proper point an upsetting plate or abutment g is provided at the top of the forming-block, said plate being preferably of approximately the same thickness as the horizontal flange of the iron. The 25 forward end or point of the plate g is rounded, so as to provide room for the metal upset at the bend. The sides of the plate are arranged parallel with the sides of the forming-block and form an abutment for the flange. For 30 adapting the machine for iron of different widths and thicknesses plates of different sizes may be used, and for this purpose I make the same removable from the block, each plate when in use being secured to the forming-block by a screw or other suitable fastening means. For retaining the plate in position against turning or being displaced on the block I provide a raised abutment g' , against which the plate is adapted to bear at its rear, said 35 abutment being preferably made integral with the forming-block and preferably extending entirely across the same, so as to give support to the extreme ends of the plate. For supporting the iron at points beyond the forming-block a rest h is provided on the guide-block, said rest having a slot and being secured to the block in any desired position by means of its set-screw. On the bending-lever 40 D is provided a sliding rest or gage h' , having two set-screws h^2 h^3 for locking it in position on the lever. This rest or gage is provided with a vertical recess h^3 , adjacent the lever, and with a shoulder h^4 , located at the same height as the top of the forming-block. The 45 rest or gage h' is furthermore provided with a portion h^5 , located in the path of the iron when in said recess, so that the iron is prevented thereby from longitudinal movement in outward or forward direction. For adapting 50 the rest to metal of different dimensions the longitudinal opening of the same is made of greater width than the thickness of the le-

ver D, so as to permit the insertion of a removable plate i^2 between the rest and lever at either side of the latter, as desired, so that 70 the width of the recess is increased or diminished. For supporting the vertical flange at its under side a removable block i^5 is located in the socket or recess of the rest and secured therein by a set-screw i^4 . By substituting 75 blocks of different heights the rest is adapted to support at the vertical flange iron of different thicknesses, the upper or horizontal flange of the iron resting on the shoulder h^4 . In order to prevent movement of the iron 80 in rearward direction during the bending act, a rear gage is provided. A rod k , of round iron, is screwed or otherwise secured to the guide-block B, and the gage k' is located thereon and adjustable longitudinally and 85 circumferentially, so as to be set at any desired point or swung so as to be entirely out of the path of the iron when not desired to be used. A set-screw k^2 in the gage serves for retaining the same where placed. The 90 forming-block E is first adjusted, the iron inserted with its vertical flange between the same and guide-block, the gages and rests are adjusted, the block E then is preferably moved up by turning hand-wheel d^4 so as to 95 tightly clamp the iron between the same and the guide-block B, the presser-plate depressed, its locking-link thrown over, and the bending-lever is then swung, thereby bending the iron G into the same. (Shown in Fig. 100 6.) The lever is swung back, the link released and the presser-plate raised, the bent angle-iron removed and a new piece inserted, the presser-plate again depressed and the forming-block tightened, and the bending-lever 105 again swung, the same operations being repeated for subsequent pieces.

When bending angle-iron by ordinary means, such as dies and levers heretofore in use, the strain of compression of the horizontal flange longitudinally at the bend causes a tearing strain in the vertical flange, tending to part the same at the bend. The tendency is for the net length of the iron to be 110 slightly increased, an actual stretching occurring at the bend. This slight lengthening, with its resulting great weakening of the vertical flange at the bend, occurs when bending iron unconfined at its ends, as all iron has been heretofore. By my improved machine, however, I block the iron at the ends, and particularly at the moving end, whereby 115 extension of the same is prevented, the extra metal being upset at the horizontal flange at the bend. The machine upsets the horizontal flange at the bend to a much larger degree 120 than has been heretofore accomplished, and stretching and weakening of the vertical flange at the bend are obviated. This is accomplished, primarily, by the gage h' on the 125 bending-lever, which blocks the forward end of the iron and exerts a positive and forcible compressing action on the same when the lever is swung. Any suitable means may be

employed for holding the iron at its rear or opposite end; but when heavy iron is to be bent it is preferable to employ the gage k' and also to screw the forming-block up so as 5 to tightly clamp the iron between the same and the guide-block. By reason of the compression action caused by blocking the outer end of the iron I can make a sharper bend than was heretofore possible without any danger of rupturing the vertical flange.

The bearings of the bending-lever may be made as indicated in Fig. 4, in which case trunnions of the same width as the body of the lever and located in the plane of the same 15 are indicated. For reducing the extent of compression, however, and for increasing the leverage it is desirable to bring the centers of the lever-trunnions nearer the metal. For doing this the trunnions are preferably made 20 of a diameter twice the thickness of the lever-body, as indicated in Figs. 2 and 3, and the lever-body is located at the rear side of the trunnions—*i. e.*, that side of the same away from the forming-block—whereby the surface 25 of the metal and the centers of the trunnions are brought adjacent, or the trunnions may bear any other desired proportion to the lever-body, so as to obtain the desired compression and leverage.

30 The machine shown is adapted for operation by the right hand of the operator. For adapting it to a left-hand operator the bolts $n\ n'$ are removed, the guide-block, top plate, and lever turned over, so that the guide-block 35 extends over the opening n^2 of the base and adjacent the face n^3 of the forming-block, and the lever extends as indicated in dotted lines n^4 . The machine is then operated from the other side.

40 It is obvious that the machine may be operated either by hand or power and may be employed not alone for bending angle-iron, but also for bending flat or round iron of suitable dimensions.

45 Having thus described my invention, I claim as new and desire to secure by Letters Patent—

1. In a machine for bending angle-iron, the combination, with a base or bed, of a guide-block on the same, a forming-block on said bed having two contiguous working surfaces, a bending-lever, an upsetting-abutment on said forming-block parallel with said working surfaces and being offset therefrom, and 55 a presser-plate co-operating with said abutment to form a recess for the horizontal flange of the iron, substantially as set forth.

2. In a machine for bending angle-iron, the combination, with a base or bed, of a guide-block on the same, a forming-block on said bed having two contiguous working surfaces arranged at an angle each to the other, a bending-lever, an upsetting-plate on said forming-block, having faces disposed parallel 60 to said working surfaces and offset some dis-

tance therefrom, and a pivoted presser-plate adapted to swing in a vertical plane centrally between said working surfaces and to co-operate with said upsetting plate to form a recess for the horizontal flange of the angle-iron, 70 substantially as set forth.

3. In a machine for bending angle-iron, the combination, with the base or bed, of a guide-block on the same, a forming-block on the bed, a bending-lever, a presser-plate, a gage 75 on the bending-lever for causing the upsetting of the metal simultaneously with the bending of the same, and a removable upsetting-plate on the forming-block, between the same and the presser-plate, said upsetting-plate being cut away at its forward portion in rounded form so as to receive the upset metal of the horizontal flange of the iron, substantially as set forth.

4. In a machine for bending angle-iron, the combination, with a base or bed, of a guide-block on the same, a forming-block on the bed, a bending-lever, interchangeable upsetting-plates for said forming-block, a presser-plate on said forming-block, and an adjustable retaining means on said guide-block for retaining the presser-plate in depressed position, substantially as set forth.

5. In a machine for bending angle-iron, the combination, with a base or bed, of a guide-block on the same, a forming-block having working portions at the edges of two adjacent sides and the top surface, a bending-lever, a presser-plate arranged on said forming-block, an upsetting-plate on said forming-block between the same and said presser-plate, a vertically-adjustable rest on said guide-block, and a longitudinally and laterally adjustable rest carried on said bending-lever, substantially as set forth.

6. In a machine for bending angle-iron, the combination of a bending-lever, a sliding rest carried on the same, said rest being recessed next to the lever-body for receiving the vertical flange of the angle-iron, a vertically-adjustable block secured in said recess, and means for adjusting said rest laterally on the lever for changing the width of said recess, substantially as set forth.

7. In a machine for bending angle-iron, the combination, with the base or bed, of a reversible guide-block on the same, a forming-block on the bed, a reversible top plate on the guide-block, a bending-lever, and means for securing said guide-block, top plate and lever in position on said bed at either side of the forming-block, substantially as set forth.

In testimony that I claim the foregoing as my invention I have signed my name in presence of two subscribing witnesses.

WILHELM VOLLMER.
